(57) **CLAIM**

The ornamental design for an automobile, as shown and described.

DESCRIPTION

FIG. 1 is a left front perspective view of the automobile showing my new design;

FIG. 2 is a right rear perspective view thereof;

FIG. 3 is a left side elevation view thereof;

FIG. 4 is a front elevation view thereof; and,

FIG. 5 is a rear elevation view thereof.

The broken lines shown throughout the drawing views are for illustrative purposes only and form no part of the claimed design.
